UNITED STATES PATENT OFFICE.

FRANK PARDEE, OF HAZLETON, PENNSYLVANIA.

COAL CHUTE AND PICKING TABLE.

1,176,848.

Specification of Letters Patent. Patented Mar. 28, 1916.

Application filed February 6, 1913, Serial No. 746,599. Renewed February 11, 1916. Serial No. 77,790.

To all whom it may concern:

Be it known that I, FRANK PARDEE, a citizen of the United States, and resident of the city of Hazleton, county of Luzerne, and State of Pennsylvania, have invented certain new and useful Improvements in Coal Chutes and Picking Tables, of which the following is a specification, reference being had to the accompanying drawings.

10 The invention relates and applies to the chutes in a breaker, along which the coal with mixed slate and bone descends after being sized. The common practice of stationing a certain number of men or boys by 15 the side of these chutes to inspect the mixed materials and pick out the slate and bone, is attended with a loss of time and uncertain results. There is often a difficulty in detecting the foreign substances, and passing 20 pieces escape notice that should have been examined and removed. The men sometimes delay the mixed substances with their feet or otherwise, but in such case the materials stack up and the position of the men 25 with respect to the mixed materials, makes a proper examination difficult.

The objects of the present invention are to provide suitable picking stations, with means for controlling the flow and movements of the mixed substances, and present 30 them in a proper light and edge position for detecting impurities; and to aid the men or boys in removing the slate and bone so that it may be done with less trouble and with 35 more efficiency than has heretofore been possible.

The invention consists in what may be termed a combined coal chute and picking table, having certain novel features of construction to be hereinafter more fully described, and distinctly claimed, with such latitude or scope as may properly belong to the present subject-matter.

In the drawings Figure 1, is a side elevation of the structure, showing upper and lower picking tables and connections adapted to be supplied by a single ordinary breaker chute; and this figure also shows leading off connections for the slate and bone. 40 Fig. 2, is a plan view of the same. Fig. 3, is a perspective view of the feed connection for two sets of picking tables, a part of the upper one only being shown, while the lower

55 picking tables and the bone and slate connections, are omitted. Fig. 4, is a plan view of a modified form of picking table, and Fig. 5, a section taken on the line 5, 5, of Fig. 4.

The device or apparatus takes up a certain space in the regular course of transit or descent of the materials, and is to that extent a 60 substitute for the ordinary or common breaker chute. The breaker chute supplies the mixed materials; it connects with the upper and lower end of the apparatus, and the continuity of transit may be preserved 65 in whole, or, in part. The stream of mixed substances is preferably divided and distributed over several tables forming upper and lower sets, which give a better opportunity for examination. In this form of 70 embodiment some of the pickers may concentrate their attention and confine their inspection to the materials passing over the upper and others to those passing over the lower tables. The drawings show one set of 75 picking tables above another which are supplied by a single breaker chute, but there may be any desired number likewise supplied. The picking tables may connect or be connected with the usual coal chute in 80 any desired way. The sets of picking tables, as shown, are divided longitudinally by a partition on each side of which there is one picking table at which men or boys may be stationed. This duplex form of structure 85 with one set of tables below another, may in reality be regarded as providing four picking tables, or two sets, at a single picking station and the number may be increased at will or to the limit of the capacity of the 90 supply chute above them.

In the drawings a represents the base or floor on which the upright supports a' , a'' , a''' , are secured. The supports sustain the structure on a proper incline or pitch as 95 illustrated. The uppermost part of the structure which receives the mixed substances from the breaker chute, is a level or flat plate b , with a side flange b' , and with a bend b'' , and a laterally inclined surface b''' , for deflecting a portion of the supply coming from the breaker chute, to a plate or part b^4 , having a bent up corner b^5 , from which some of the substances are directed and pass to the lower picking table, 100 as presently explained. The plate b , also

has a flange b^6 , which extends from the bend b^2 , to the lower end of that particular plate or part of the structure.

A second plate or part c , connects at its upper end with the plate b , but is of a different formation. The plate or part c , has side flanges c' , c^2 , and widens or spreads from its upper to its lower end. The part c , has a bottom which is level or flat practically across the upper end, but it is bent diagonally from its two upper corners toward the center of the lower end, so that the flat surface c^3 , forms a V. The adjacent surfaces c^4 , c^4 , on each side of the V, incline upwardly toward the side flanges c' , c^2 , and widen or diverge from the upper to the lower end of the section c . At a certain distance, approximately one third down from the top of the part c , a gate d , is shown, which swings on a rod d' , passing through the flanges c' , c^2 . The rod d' , also forms a handle d^2 , near the side c^2 , for controlling the gate d . It is sometimes desirable to check or hold back the flow of mixed substances from above and the gate makes provision for that purpose.

The lower end of the part c , connects with a third and shorter section or part e , having a bottom surface which inclines laterally upward on each side, and at the center of which a division is made between these lateral inclines by an uprising flat or level partition e' . The partition e' , starts from zero or thereabout on the upper middle of the bottom of the part e and attains sufficient height at the lower end thereof to deliver the materials in divided streams. This division of the mixed substances and their delivery to the picking tables on each side of the partition e' , is also aided by convergent flanges or guides e^2 , e^2 , on the part or section e .

The bottom formations and inclined surfaces on the parts c , and e , their flanges and guides serve to settle and adjust the materials in such a way as to give them a fairly stable equilibrium. In most cases the mixed substances will pass from the part e , on one of their broadsides and thus present an edge view, which is desirable for the purpose of inspection, as in the case of bone, the presence of a stratum of slate will more often appear at the edge.

The picking tables f , f , connect with and come just below the part c , and a continuation of the divided streams is maintained by a partition f' , which connects with the uprising partition e' , of the section or part e . The upper end of the partition f' , is shown as being provided with a projection f^2 , and a winged part or flapper f^3 , secured at its upper end and so as to turn on a pivot and be tipped or tilted to release or hold back the mixed materials at the upper end of one or of the other table.

The picking tables f , f , are preferably duplex, or in sets of two and may be formed of plates provided with an inside flange f^4 , from which a lateral upward incline to the edge is made. The outer edge is shown as being finished and left free by the formation of downwardly extending flanges f^5 , at the side. The inner flanges f^4 , extend partially up on the sides of the partition f' , and are in effect a part of that partition in the structure as illustrated by the drawings.

The lower initial parts and table sets are substantially the same as the upper ones. A part of the mixed materials which come from the breaker chute are deflected by the plate or part b^4 , as already stated. The bent up corner b^5 , of the plate b^4 , is near an inclined plate g , and makes a partial closure at the upper end of that plate so that a sort of feed-chute is formed and part of the materials coming from the breaker chute is led to and through several sections, namely, h , which corresponds to the upper section b ; i , which corresponds to the plate or part c ; j , which corresponds to the plate or shorter section e ; and a set of picking tables k , k , like those designated as f , f , directly above them. The lower picking tables are laterally inclined from inner flanges k' , k' , and the partition between them is a plate k^2 , which extends up and connects under the plates f , f . At the upper end of the partition plate k^2 , there is also a flapper or gate k^3 , for controlling the downflow of the mixed substances from the sections or parts leading to these lower picking tables.

The leading off chutes l , l , are for slate and bone respectively. These chutes are shown as being provided with gates l' , l' , and locking loop-wires l^2 , l^2 . It is sometimes desirable to reinspect the pickings which are cast into these chutes and by having locking devices for the gates, the materials picked from the coal chute may be retained for a time above the gates and a reinspection of them made before they are finally released.

In the modified form of picking table illustrated by Figs. 4, and 5, the principal variations commence at the uprising part or partition m , which corresponds with the partition e' , previously described, but takes its uprising from the bottom of a section m' , corresponding with the section e , though it is shown as having straight side flanges m^2 , below which there is a section n , corresponding to the section e . The section n , in the modified form also has straight side flanges n' , n' , instead of the forms of flanges or guides e^2 , e^2 , of the section e . The partition n^2 , which divides the tables in the center, is practically the same as previously described, but it commences at the terminus of the uprising partition m , which is at the lower end of the section m' , or upper end

of the section n . The form of gate n^3 , varies somewhat from the flapper f^3 , being hinged to the side flanges n' , n' , by straps n^4 , n^4 , instead of being pivoted like the flapper f^3 , 5 on the form already described.

In the modified form the duplex picking tables o , o , are each provided with an upper outwardly inclined ridge or ledge o' , which is joined at one side of a flange o^2 , to 10 the central partition, and is finished at its outer edge by a bend or descending flange o^3 , from which the outer part of the table inclines upwardly and is in turn finished by a turned down flange o^4 , in the same manner 15 as the outer edge flanges of tables already described. The ledge or inner part of the tables o , o , receives materials directly from the lower bottom end of the section or part n , next above, while the outer part of these 20 tables is shown as receiving materials by a drop from the lower part of the bottom of the end of the section n , or they may receive materials which topple and gravitate from the ledges o' . In this modified form of 25 structure, there may be any desired number of sets of upper and lower tables, or, in this and the one previously described, a single instead of a duplex table may be used, or there may be upper and lower single tables. 30 As a whole the structure illustrated, presents or comprises the picking table, a level or flat runway, and a partly level or flat and partly inclined runway, and an inclined runway connected therewith and with the table. 35 The words level or flat are used in a relative sense to distinguish from intersecting inclined surfaces or planes.

The details of construction which have been given in describing what at present is 40 contemplated as the best mode of applying the principle of the invention, may be varied in a number of ways neither illustrated nor described.

In practice, the mixed materials coming 45 along the breaker chute above the picking station structure, as above described, pass upon and over the transverse flat surface of the plate b and some of such materials are deflected by the transversely inclined surface b^3 to the part b^4 and drop to the lower picking table and near the bent up corner b^5 . The mixed materials which go to the upper picking table pass along the plate b on the

flanged side b^6 , and on to the transverse flat surface of the next lower plate c and are 55 parted or distributed by their passage over the transversely inclined diverging surfaces or V-surface of the plate c . The same mixed materials then pass on to the plate e taking such lateral directions as may be given to 60 them by the uprising partition c' , from which they are delivered in divided streams to the hand picking tables f , f . The action on the mixed materials during their passage over and along the surfaces stated, is such 65 as in most cases to present an edge view to the men or boys at the sides of the table which aids materially in the detection and picking of the slate and bone from the pure or commercial coal.

Having thus described my invention, what I claim as new and desire to secure by Letters Patent is:—

1. In a coal chute, a picking station comprising a runway whereon the bottom surface is transversely flat for a certain distance, a lower runway connected therewith and having a partly flat and partly transverse inclined bottom surface, and a still lower third runway connected with the second one, said third runway having diverging inclined transverse bottom surfaces, and a picking table connected with said third runway.

2. A combined chute and picking table for 85 coal, etc., comprising a preliminary runway, a second runway connected therewith and adapted to change the position of passing mixed materials, a third runway divided and inclined, and a set of hand picking tables 90 connected with said divided runway, each of said picking tables being accessible from opposite sides.

3. In a coal chute, a picking station, comprising a hand picking table and a feed-plate connected therewith, said feed-plate having bottom surfaces transversely inclined toward the center and an uprising central partition, whereby the mixed materials are delivered in divided streams to the said 100 picking table.

FRANK PARDEE.
